UNITED STATES PATENT OFFICE

2,578,092

CORN SHOCKER WITH DIVIDED FORMER

Edward H. Rehn, Lima, Ohio

Application June 1, 1949, Serial No. 96,528

5 Claims. (Cl. 56—428)

1

This invention relates to new and useful improvements and structural refinements in shockers for corn and other grain, and the principal object of the invention is to provide a device of the character herein described, which is primarily intended to be used in association with a binder, so as to facilitate convenient, efficient, and expeditious performance of the shocking operation.

This object is achieved by the provision of a shocker which includes in its construction a frame and a shock receiving and depositing platform mounted on the frame in such manner that after a shock has been erected thereon, the platform may be moved from the frame to the ground and the shock may be deposited on the ground while the shocker continues on its travel with the binder.

One of the important features of the invention, therefore, resides in the provision of means for mounting the shock platform on the frame, and another feature of the invention resides in the particular construction of the platform per se.

Some of the advantages of the invention lie in its simplicity of construction, in its adaptability for use in association with binders of different types, in its convenient operation, and in its adaptability to economical manufacture.

With the above more important objects and features in view and such other objects and features as may become apparent as this specification proceeds, the invention consists essentially of the arrangement and construction of parts as illustrated in the accompanying drawings, in which:

Figure 1 is a perspective view of the invention connected to a binder;

Figure 2 is a top plan view of the invention per se;

Figure 3 is a side elevational view of the invention;

Figure 4 is a perspective view of the invention in a position wherein a shock may be deposited on the ground;

Figure 5 is a fragmentary cross sectional enlarged detail, taken substantially in the plane of the line 5—5 in Figure 3;

Figure 6 is a cross sectional enlarged view, taken substantially in the plane of the line 6—6 in Figure 2, and

2

Figure 7 is a cross sectional enlarged detail, taken substantially in the plane of the line 7—7 in Figure 2.

Like characters of reference are employed to designate like parts in the specification and throughout the several views.

Referring now to the accompanying drawings in detail, the invention consists of a corn shocker designated generally by the reference character

10, the same embodying in its construction a frame 12 including a rectangular base plate 14 provided with a pair of projecting brackets 16 equipped with wheels 18 on which the entire shocker travels.

15. The shocker is intended to be used in association with a binder 20 of any conventional type and is connected thereto in any suitable manner. However, it is to be noted that a hinged foot plate 22 is provided on the base plate 14 of the shocker

20 frame 12, whereby the base plate of the shocker is extended toward the binder, as is best shown in Figure 1. In addition, a pair of guards 24 and 24' may extend upwardly from the base plate 14 on opposite sides thereof and a suitable receptacle

25 26 may be positioned on the guard 24, said receptacle being intended to function as a storage space for binder twine, or the like.

An upright standard 28 is provided at its lower end with a base 30 whereby it may be 30 rigidly mounted in one corner portion of the frame base plate 14, this standard being preferably tubular and being provided at its upper end with an L-shaped extension or boom 32, the vertical arm, or portion of which is rotatably

35 telescoped in the standard 28 but is prevented from sliding downwardly therein by means of a clamp 34 with which the boom is equipped. This clamp is rigidly secured to the boom and abuts the upper end of the standard 28, as will be clearly apparent.

An extension shaft 36 is slidably received in the horizontal arm or portion of the boom 32 for lateral adjustment.

What may be generally referred to as a shock receiving and depositing platform 38 has a bottom consisting of a plurality of spaced parallel straps, bars or channels 40, upwardly extending continuations of which are indicated at 42 and constitute a side wall at one edge or end of the bottom of 45 the platform, substantially as shown.

The members 42 of the platform 38 are rigidly secured together with a plurality of cross pieces 44, 44' and 46, the cross pieces 44 and 44' being provided at one end or side edge of the side wall with bearing brackets or clamps 48 and 48' which are rotatable and vertically slidable on the standard 28.

The members 42 constituting the side wall of the platform 38 have secured thereto a side wall forming panel 50, and a plurality of reinforcing gussets 52 extend between the members 40, 42 of the platform 38, as is best shown in Figure 4.

An upstanding, upwardly convergent shock support 54 is attached to the members 40, 42 of the platform 38 and is provided at its upper end or edge with a yoke 56 connected to a pulley block 58.

Suitable reinforcing struts 60 extend between the cross piece 44 and the support 54, whereby the support 54 and the members 40, 42 of the platform 38 assume the form of a rigid unit.

A rope or cable 62 has one end thereof anchored as at 64 to the outer end of the aforementioned shaft 36, and after passing around the pulley block 58, the rope or cable 62 passes over a pair of guide pulleys 66, 68 provided on the boom 32, as will be clearly apparent. The rope or cable 62 is then taken to a winch mechanism 70 which includes a rotatable drum 72 mounted in a supporting bracket 74 which is secured to one of the wheel brackets 16.

The drum 72 of the winch 70 is operatively connected by a chain drive 76 to a hand crank 78, and it is to be noted that the shaft 60 on which the drum 72 is mounted also carries a brake disk 82 in engagement with an external contracting brake shoe or band 84.

As is best shown in Figure 7, one end of this shoe or band is anchored as at 86 to the bracket 74, while its remaining end is operatively connected to a pivoted lever 88 which is selectively engageable with struck-out detents 90 provided on a "quadrant" or bar 92, whereby the brake mechanism of the winch may be adjusted in a predetermined position, that is, either with the brake "on" or "off" as desired.

When the invention is placed in use, the platform 38 is disposed above the base plate 14 of the shocker frame 12, and as the binder 20 continues on its travel, the corn may be shocked on the bottom members 40 of the platform 38 with the member 54 acting as a support for the shock, the attendant of the shocker, of course, standing on the foot plate 22 and on the base plate 14 around the movable platform 38.

As soon as a shock has been formed on the platform 38, the winch mechanism 70 may be actuated by means of the crank 78 so as to lift the entire platform together with the shock slightly above the base plate 14, after which the boom 32 together with the platform 38 and the shock thereon may be swung laterally to the position shown in Figure 4 (and also by the phantom lines 94 in Figure 2) until the platform 38 is disposed entirely behind and at one side of the shocker frame 12. The winch mechanism 70 may then be actuated so that the platform 38 is lowered to the ground, whereupon the shock will be deposited on the ground by frictional contact.

It is to be noted that during this entire procedure the binder and shocker are in forward motion, which, of course, facilitates depositing of the shock on the ground, and as soon as the last mentioned operation has been performed, the

winch 70 may again be actuated so as to elevate the platform 38, and the boom 32 may be swung so that the platform may be returned to its initial position on the base plate 14, in readiness for the next shocking operation.

It is believed that the advantages and use of the invention will be clearly apparent from the foregoing disclosure and accordingly, further description thereof at this point is deemed unnecessary.

While in the foregoing there has been shown and described the preferred embodiment of this invention, it is to be understood that minor changes in the details of construction and arrangement of parts may be resorted to without departing from the spirit and scope of the invention as claimed.

Having described the invention, what is claimed as new is:

1. In a corn shucker, the combination of a frame adapted for connection to a binder, a shock receiving and depositing platform, a standard means on said frame for supporting said platform whereby it may be swung laterally from a position above the frame to a position above the ground while the binder is moving, means for raising and lowering said platform in and out of engagement with the ground and with said frame, said platform including a plurality of slats positioned in spaced relation whereby when said platform and shock are lowered, the shock will frictionally engage the ground for retention thereby.

2. A corn shucker comprising the combination of a frame adapted for connection to a binder, a shock receiving and depositing platform, a standard means on said frame for supporting said platform whereby it may be swung laterally from a position above the frame to a position above the ground while the binder is moving, means for raising and lowering said platform in and out of engagement with the ground and with said frame, said platform including a bottom consisting of a plurality of spaced straps, together with an upstanding shock support provided centrally on said bottom.

3. A corn shucker apparatus comprising a wheeled frame adapted for connection to a binder, a shock receiving and depositing platform, a standard means on said frame for supporting said platform whereby it may be swung laterally from a position above the frame to a position above the ground while the binder is moving, means for raising and lowering said platform in and out of engagement with the ground and with said frame, said platform including a bottom consisting of a plurality of spaced straps, an upstanding side wall at one edge of said bottom, and an upstanding shock support attached centrally to said bottom and to said side wall, said side wall rotatably and slidably mounted on said standard means.

4. A corn shucker comprising a wheeled frame adapted to be connected to a binder for movement therewith, a shock receiving and depositing platform, a standard fixedly mounted on said frame at one corner thereof, said platform including a plurality of angulated bars connected in spaced relation by a plurality of transversely extending cross pieces, one end of each of said cross pieces being provided with a bearing bracket, each of said bearing brackets being slidably and rotatably mounted on said standard, and means for slidably and rotatably moving said platform from the position for receiving to the position for depositing the shock.

5. A corn shucker comprising a wheeled frame adapted to be connected to a binder for movement therewith, a shock receiving and depositing platform, a standard fixedly mounted on said frame at one corner thereof, said platform including a plurality of angulated bars connected in spaced relation by a plurality of transversely extending cross pieces, one end of each of said cross pieces being provided with a bearing bracket, each of said bearing brackets being slidably and rotatably mounted on said standard, and means for slidably and rotatably moving said platform from the position for receiving to the position for depositing the shock, said means including

an upstanding shock support mounted on said platform, and a winch mechanism connected to said shock support.

EDWARD H. REHN.
